J. J. Adams,

Glass Furnace.

Patented Apr. 21, 1832.

John J. Adams
Gottos Patent Dated April 21. 1832

The Schedule referred to in these Gottos Patent, and making part of the same, containing a description in the words of the said John J. Adams himself, of his Improvement in the process of flattening Window Glass.

Be it known, that I, John J. Adams, of the City of Washington, and District of Columbia, have made an improvement in the process of flattening Window glass, which is described as follows. 1 The wall, inclosing the machine for flattening, made circular, of any convenient size, and is nearly, built of brick or stone. On the back, and on each side, is a hole to admit fire and fuel. The ditch or rear hole for admitting the glass cylinders, is left in the wall, near the top, and within about 3 feet of the tempering arch. Two openings for flattening mouths are also left on the same side with the flattening arch, about 5 or 6 feet apart. On the cooling oven side, an opening is left for laying the glass off the flattening stone upon the cooling or tempering plat. 2 A inner circular wall, of about 4 feet diameter is placed in the center of the outer circular wall before described. 3 There is an arch, resting on the inner and outer circular walls, leaving a center open ing, within the inner circular wall, of about 3 feet diameter, thinner than the outer wall, of brick or fire clay. This arch is divided into two parts by mantes or divisions, leaving three of the flattening stones, with their intermediate spaces, in each apartment. 4 A circular arch, of about 7 feet diameter, made of cold iron is placed in the center of the before described circular wall, leaving a groove or flange on it, for admitting a car riage with rollers supporting the flattening, apparatus to be most describ ed. 5 The flattening apparatus, is made of three iron, and of a size nearly to fill the circular space inclosed within the circular walls; this may be divided into four or six divisions to receive the flattening, stones. The flattening stones with their heads rest on bars a support placed on a wing and resting on the before mentioned rollers. 6. The cooling arch is about 30 feet long, and 3 feet wide. Two metal chains, about 3 feet apart, are on the cooling arch, one on each side of the center open ing.

models them on 4 or 6 drums or rollers, turning on guides supported on the walls. On these chains are hung a number of short iron plates about 3 feet long and 2 1/4 feet wide. The sheets of glass are taken off the flattening stones and placed on these revolving plates to cool. The chimney for the fire and a pass up this the inner circular wall; the smoke passing under the main arch or cover, and out at the cooling arch and cooling mouth. Operation. - The cylinder of glass is shown thro' the stick hole or rear, and put on one of the intermediate spaces to heat, the flattening apparatus is then turned till another space comes in a line with the stick hole, this brings the first-mentioned cylinder in a line with the first flattening mouth; the glass is then laid open upon the flattening stone, the flattening apparatus is again turned till the first cylinder on the flattening stone comes in a line with the second flattening mouth, where it is flattened out; this movement also brings the third space in a line with the stick hole, the apparatus is again turned another space, which brings the first cylinder into the cooling apartment; when by turning the apparatus three sheets of glass are in the cooling apartment, then the first sheet is placed upon the first cooling plate. When the first cooling plate is full, then the an other chain with the cooling plates upon them are turned the space of one plate, by a crack windup placed below; and so on till the business is completed.

The invention ... here claimed and desired to be secured by Letters Patent is the before described process of flattening and cooling glass, particularly the revolving flattening apparatus, and the revolving cooling plates placed on suitable chains, likewise the arches covering the flattening & cooling apparatus. For a further illustration of my invention I refer to the model and drawing of the same deposited in the Patent Office. In witness whereof I have hereunto subscribed my name before two witnesses this 11th day of April 1834.
